TONE CONTROL SYSTEM

Ellison S. Purington, Gloucester, Mass., assignor
to John Hays Hammond, Jr., Gloucester, Mass.

Application April 3, 1936, Serial No. 72,520

21 Claims. (Cl. 179—100.1)

This invention relates to the reproduction of sound from a sound record and has for its purpose to provide automatic means for controlling the tonal characteristics of the reproduced sound.

5 More specifically the invention provides an automatic means for discriminating against the reproduction of sound of a given frequency range, unless there are suitable signals in that frequency range.

10 The invention further provides for the masking of background noises, by suppressing the transmission of noise frequency signals unless the desired signals are of suitable nature to mask the presence of the noises.

15 The invention also provides for increasing the tonal contrasts of the reproduced sound.

In accordance with the present invention, the tone control is effected by providing a transmission channel having a variable filter network which includes the primary of a transformer, the secondary of which is variably loaded by a thermionic impedance. The thermionic loading is controlled by voltages obtained by rectifying suitable energy derived from the tonal energy output of the sound record.

25 The control action depends upon the principle that the effective primary impedance of a transformer, which in this case determines the impedance properties as far as the transmission network is concerned, is dependent upon and controllable by the impedance loading of the secondary circuit. The general effect of lowering the value of a resistance impedance shunted across the secondary winding of a transformer, is to increase the secondary loading and to reduce the equivalent primary impedance, especially for the higher frequencies. The relative transmission of currents of different frequencies through the network in which the primary of the 30 transformer is connected is therefore modified by secondary thermionic impedance control.

35 A feature of the invention accordingly consists in replacing an inductance element of a conventional filter, such as a low pass, band pass or high pass filter, by the primary of a transformer having a variable secondary thermionic loading, whereby the properties of the filter may be controlled, as to cut-off frequency, sharpness of cut-off etc., in accordance with the energy 40 by which the thermionic impedance is modified.

45 Another feature consists in connecting the secondary to a pair of thermionic impedances, each carrying direct current, with a balanced secondary winding arrangement such that the 50 equivalent primary impedance is controlled solely

by the alternating current thermionic impedance values, and is not modified by the changes of direct current through those impedances. A wide range of transmission values is thus achieved by one transformer, the balanced operation minimizing any distortions that may result from non-linearity of tube characteristics. Furthermore a rapid tonal control is obtained due to the fact that no change of the direct current flux of the core occurs during operation.

5 The invention also consists in the various new and original features of construction and combinations of parts hereinafter set forth and claimed.

10 Although the novel features which are believed to be characteristic of this invention will be particularly pointed out in the claims appended hereto, the invention itself, as to its objects and advantages, the mode of its operation and the manner of its organization may be better understood by referring to the following description taken in connection with the accompanying drawings forming a part thereof, in which

15 Fig. 1 illustrates diagrammatically the system as applied to the reproduction of sound from the sound record of a talking moving picture projector and phonograph.

20 Fig. 2 is a series of curves illustrating the relative frequency transmission characteristics of certain portions of the circuit shown in Fig. 1.

25 Fig. 3 is a schematic diagram of a modified form of the filter circuit shown in Fig. 1.

30 Fig. 4 is a series of curves illustrating the relation between the frequency and the transmission characteristics of the modified circuit shown in Fig. 3.

35 Fig. 5 shows a circuit to illustrate the insertion loss which may be produced in accordance with this invention.

40 Fig. 6 is a series of curves illustrating the insertion losses of the circuit depicted in Fig. 5.

45 Fig. 7 shows a circuit to illustrate the insertion loss which may be produced with a different circuit arrangement.

50 Fig. 8 is a series of curves illustrating the insertion losses of the circuit depicted in Fig. 7.

55 Like reference characters denote like parts in the several figures of the drawings.

In the following description and in the claims parts will be identified by specific names for convenience, but they are intended to be as generic in their application to similar parts as the art will permit.

Referring to the accompanying drawings, and

more particularly to Fig. 1, a phonograph pick-up 10 is shown which is connected to two contacts of a double-pole, double-throw, transfer switch 11, the other contacts of which are connected to the 5 circuit of a photo-electric cell 13 including battery 15. Light from a lamp 16 is focused by means of a lens 17 through an aperture 18 in an aperture plate 19 upon the sound record of a moving photographic film 20. The light which passes 10 through this film then impinges upon the photo-electric cell 13.

The blades of the transfer switch 11 are connected to the primary winding of input transformer 21, one side of the secondary of which is 15 connected to ground and the other to the grid of a separate heater type triode amplifier tube 22. The cathode of this tube is connected to ground through bias resistor 30, in parallel with by-pass 20 condenser 31. The plate supply for tube 22 is taken from battery 28, the negative side of which 25 is grounded, and the positive side of which is connected through feed resistor 28a and coupling resistor 29 to the plate of tube 22. A by-pass condenser 28b is connected from the junctions of feed resistor 28a and coupling resistor 29 to ground. Battery 28 serves also as plate supply to other tubes to be mentioned later.

A blocking condenser 23, the primary of the tone control transformer 25 and one resistance winding 26 of a manual volume control rheostat 30 are connected in series between the plate of the amplifier tube 22 and ground. The ends of the secondary windings of transformer 25 are connected to the plates of two space discharge tubes 32, the alternating current impedances of which 35 control the tonal transmission in a manner to be described. Space current for the tubes 32 flows through feed resistor 36, one terminal of which is connected to the positive side of battery 28 and 40 the other terminal to the center tap of secondary of transformer 25. The secondary winding is so arranged that the D. C. space currents to the two plates produce opposite magnetizing effects upon the core of the transformer. The cathodes of 45 tubes 32 are joined together, and to the junction of bleeder resistors 33 and 34, which in turn are connected in series between center tap of the secondary of transformer 25 and ground. Resistor 34 serves also as a cathode bias resistor, and 50 the circuit is so designed that the value of the voltage across this resistor 34 does not increase more than 25 to 50 percent as the space current of tubes 32 changes from zero to maximum value. The grids of tubes 32 are connected together and 55 between them and ground are two resistors 64 and 63, the functions of which will be described later. The cathodes of tubes 32 are connected to one side of filtering and timing condenser 35, the other side of which is connected to the grids. 60 The impedances of tubes 32 are controlled by the voltage across the condenser 35, which varies in accordance with the nature of the signal output of amplifier tube 22 in the manner to be described.

65 The winding of the transformer 25 which is connected to the plates of tubes 32 is referred to as a secondary winding because the tubes 32 serve as power consuming devices, and not as an amplifier of tonal frequencies. The balanced nature 70 of the windings prevents variations of voltage across grid-cathode condenser 35 from producing similar variations of current through the primary winding of the transformer. The impedance loading upon the secondary of transformer 75

25 is virtually the sum of the internal impedances of tubes 32.

The volume control resistance winding 28 is connected through mechanically connected slide- 5 able contacts to resistance winding 27, one end of which is connected to primary of coupling transformer 37, of which the other end is connected to ground. The secondary terminals of transformer 37 are connected in a balanced fashion to the grids of two driver amplifier triode tubes 38 of 10 the separate heater type, and the center tap of the secondary of the transformer is connected to ground. The cathodes of tubes 38 are connected together and connected to one side of bias resistor 45, the other side of which is connected to 15 ground. In parallel with resistor 45 is a bias by-pass condenser 46. The plates of tubes 38 are connected to the primary winding of coupling transformer 39, the center tap of which is connected to the positive side of battery 28. The 20 secondary winding of transformer 39 is connected in a balanced fashion to the grids of two power amplifier triode tubes 40, and the center tap of the secondary winding is connected to the negative side of bias battery 47, the positive side of 25 which is connected to ground. The filaments of tubes 40 are connected in parallel, and are bridged by center tapped filament resistor 48, the center tap being connected to ground. The plates of tubes 40 are connected to the primary 30 of output transformer 41. The center tap of the primary of the transformer 41 is connected to the positive side of power supply battery 44, the negative side of which is grounded. The secondary of transformer 41 is connected to the voice coil 35 winding of loud speaker 42. The field winding 43 of loudspeaker 42 is connected across battery 44.

For producing variation in the control voltage 40 across condenser 35, some of the energy amplified by tube 22 and fed through condenser 23 is diverted to the grid of amplifier tube 51 of the separate heater type. For this purpose, a filter 45 coupling network 49 is connected between the junction of condenser 23 and primary of trans- 45 former 25, the grid of tube 51, and ground, this filter being of the high pass type and terminat- 50 ing in resistor 50 connected between grid of tube 51 and ground. This resistor 50 serves to ter- 55 minate the filter, and to make the operating or average grid potential substantially that of ground. The cathode of the amplifier tube is connected to one end of bias resistor 52 the other 60 end of which is connected to ground. In parallel with resistor 52 is by-pass condenser 53. Plate 65 current for tube 51 is supplied from the positive side of battery 28, and flows to the plate through feed resistor 58, and coupling resistor 55. The connection between resistors 55 and 58 is connected to one terminal of by-pass condenser 57, 70 the other terminal of which is connected to ground. The plate of amplifier tube 51 is connected to one terminal of the blocking and filtering condenser 55a, the other terminal of 75 which is connected to one terminal of poten- 80 tiometer 56, the other terminal of which is connected to ground. The variable contact of the potentiometer 56 is connected to the grid of triode amplifier tube 54 of the separate heater type. The cathode of tube 54 is connected to one end of bias resistor 59, the other end of which 85 is connected to ground. By-pass condenser 60 is connected in parallel with the resistor 59. The plate of tube 54 is connected to one ter- 90 minal of the primary of coupling transformer 75

61, the other terminal of which is connected to an end of feed resistor 65, the other end of which is connected to the positive side of battery 28. The junction of resistor 65 and primary of transformer 61 is connected to one terminal of by-pass condenser 65a, the other terminal of which is connected to ground. One terminal of the secondary of transformer 61 is connected to the cathode of the triode type rectifier tube 62 of the 5 separate heater type. The other terminal of the secondary is connected to one end of rectifier load resistor 63 and also to one end of resistor 64 which serves as a coupling, timing and limiting resistor. The other end of resistor 63 is connected to ground, and the other end of resistor 64 is connected to the grids of tubes 32. The plate and grid of tube 62 are joined together and 10 to ground. The conduction through the tube 62 is such that current passing through resistor 63 15 is unidirectional as indicated by the arrow. 20

The filaments of all tubes are heated by means not shown in detail. Preferably they are heated from transformer secondary windings, center taps of which are connected to ground or to the 25 cathodes of the tubes whose filaments they heat.

In the operation of the form of the invention shown in Fig. 1, the energy received by the transformer 21 from either the phonograph pick-up 10 or the photo-electric cell 13 passes to the amplifier 22, where it is amplified and fed through the blocking condenser 23 and primary of the tone control transformer 25 to the volume control adjustable rheostat windings 26 and 27. From the winding 27 the energy passes through the transformer 37 to the input of the driver amplifier tubes 38. Here it is further amplified and then passes through the transformer 39 to the input of power amplifier tubes 40. The output of the power amplifier tubes 40 then passes through the transformer 41 to the loud speaker 42, where it is reproduced as speech or music in the usual manner.

For controlling the operation of the automatic variable filter, some of the energy from the output circuit of the amplifier 22 passes through the high pass filter network 49 to the amplifier 51. Here the energy is amplified and fed through the potentiometer 56 to the second amplifier 54. Here the high frequency energy is further amplified and is fed through the transformer 61 to the rectifier 62, where it is rectified to produce a current flowing unidirectionally through resistor 63 in the direction of the arrow. The pulsations of rectified current are smoothed by resistor 64 and condenser 35 to produce a control potential on the grids of tubes 32. The amount of potential change produced is dependent upon the strength and frequency distribution of electrical energy in the output of amplifier 60 tube 22, and the grids become more positive as the energy is increased without change of distribution, or as the energy distribution is shifted toward the high frequencies without change of energy. In the absence of signals, the tubes 32 are biased sufficiently by resistor 34 to reduce the space currents substantially to zero so that the secondary of transformer 25 is not loaded, and the effect of the presence of the transformer primary is principally the choking effect due to the actual inductance of the primary winding. This discriminates against the passage of higher frequency signals, including surface noise, for example in the range of 1000 to 4000 cycles.

The discrimination against the higher tones is shown by curve 10 in Fig. 2 which shows the

lowered transmission of the higher frequencies from tube 22 to the volume control resistance 26 caused by the filter including the primary of transformer 25, when the rectifier current through resistor 63 is small and the control tube impedances are high. This corresponds to the transmission when the needle is in the record groove in the absence of any appreciable recorded signal capable of causing rectification by the tube 62.

When there are recorded signals of sufficient strength or of sufficiently high tone to mask the presence of the background noise discriminated against by the choking action, the rectifier circuit is operated to reduce the bias on tubes 32. 15 This decrease is in accordance with the characteristics of the control channel as for example shown by curve 71, which shows the relative transmission of signals of different frequencies from plate of tube 22 to the rectifier 62, as determined by the choice of constants for filter 49, as well as other elements of the amplifier circuits of tubes 51 and 54. A given amount of control may be produced by a small amount of high frequency energy or a larger amount of lower frequency energy. When the rectified energy is large so that the impedances of the control tubes 32 are low, and the equivalent primary inductance very small, the transmission of the main channel is according to curve 72, with greatly improved transmission for the higher frequencies over that shown by curve 70. While the condition illustrated in curve 72 permits the passage of background noises, this occurs only when desirable signals sufficiently strong in the background noise range, or much stronger in the lower tonal ranges, exist; hence the presence of the background noises will be completely masked. The constants of the rectifier-circuit are so chosen, as by making capacity of condenser 35 small, 40 that control action is rapid and changes of transmission characteristics occur immediately upon change of the nature of the signals. 35

This speed of action is not hindered by any delay of the plate circuit operation, since the change of plate current does not change the magnetic energy content of the iron core, and therefore no inductive voltages are produced across either half of the secondary windings of transformer 25. 45

In conventional amplifiers, fixed scratch or noise filters are used, with condensers and inductors which are adjusted for optimum transmission under conditions of weak or no signals, corresponding for example to curve 10 of Fig. 2. 55 By this invention, with a rapidly acting automatic tone control system, the frequency range of any type of record may be effectively increased, since the filtering action applied against tones in the higher frequency range is automatically reduced so that the filtering action is never greater than necessary for a given signal energy distribution. The circuit therefore, for a given type record, operates to reproduce on the average much higher frequency tones than would be permissible if background or surface noises were suppressed by conventional type scratch filters 60 65

In the modified form of the invention shown in Fig. 3 the phonograph and photo-electric pick-up mechanisms, the switch 11 and the transformer 21 are identical with those shown in Fig. 1 and have therefore been omitted from this figure. Also the power amplifier and loud speaker circuits to which the secondary of transformer 39 of Fig. 3 are connected are identical -- 70

with those of Fig. 1 and also have been omitted. In Fig. 3 the secondary terminals of the input transformer 21 are connected to the grids of two space discharge tubes 81 and 82 of a push-pull amplifier 80. These tubes are of the separate heater type. The cathodes are connected together and to one terminal of bias-resistor 80a and of bias resistor by-pass condenser 80b, the other terminals of which are grounded.

Plate supply for the plates of tubes 81 and 82 is taken from battery 118, the negative side of which is grounded. This battery serves as supply also for other tubes of Fig. 3. Filaments of tubes 81 and 82 are heated by a source not shown, preferably a secondary winding of a transformer, the center tap of which is grounded or connected to the cathodes of the tubes which are heated thereby. It will be understood that the filament and plate supply may be from any suitable source.

Bridged across from plate of tube 81 to plate of tube 82 is a variable low frequency absorption circuit and plate feed circuit 83 comprising two resistors 89, two chokes 90 and the primary of a tone control transformer 92, across which is shunted a tuning condenser 93. The center tap of the primary of transformer 92 is connected to the positive terminal of battery 118.

Also bridged from plate of tube 81 to plate of tube 82 is a variable high frequency power absorption circuit and intertube coupling circuit comprising in series one primary of coupling transformer 83, the primary of the tone control transformer 91 and the other primary of coupling transformer 83.

The secondary terminals of tone control transformers 92 and 97 are connected in a balanced fashion to the plates of two sets of tone control space discharge triode tubes 95 and 98 of the separate heater type. Center taps of the secondaries of these transformers are connected to one terminal of a feed resistor 119, the other terminal of which is connected to the positive terminal of the battery 118. Between the center tap of the secondary of transformer 92 and ground are connected in series the bleeder resistor 124 and the tapped cathode bias and limiter resistor 117. Similarly connected between the center tap of the secondary of transformer 97 and ground are bleeder resistor 125 and cathode bias resistor 126. The cathodes of the tubes 95 are joined together and to the junction of resistors 124 and 117, and the cathodes of the tubes 98 are joined together and to the junction of resistors 125 and 126. The grids of tubes 95 and 98 are connected together, and between them and ground are connected in series, the resistors 116, 115, and 109, the functions of which will be described later. Filtering, timing and by-passing condensers 95a, 98a, 95b, and 98b are connected between the grids and cathodes of tubes 95 and 98, respectively, and between the cathodes of tubes 95 and 98 respectively and ground.

The secondary terminals of the coupling transformer 83 are connected to two terminals of manual volume control potentiometers 85 and 86, the other ends of which are connected together, to ground and to the center tap of the secondary of transformer 83. The adjustable contacts of potentiometers 85 and 86 are connected to the grids of a pair of tubes 87a and 87b of a push-pull driver amplifier 87. These tubes are of the separate heater type. The cathodes are connected together, and between them and ground are connected in parallel a cathode bias resistor 87c and a cathode bias resistor by-pass condenser 87d.

The plates of tubes 87a and 87b are connected to the primary terminals of transformer 39, the center tap of which is connected to the positive end of battery 118.

As shown in Fig. 1, and explained above, the secondary windings 39 are connected to the grids of a power amplifier 40 which in turn operates a loud speaker 42.

For controlling the potentials of the grids of tubes 95 and 98 there is provided between plate 10 of tube 82 and grid of a triode amplifier tube 103 of the separate heater type, and ground, a high pass filter 101 of the condenser-resistor type with condenser elements in series and resistor elements in parallel. Connected between grid of tube 103 and ground is a filter-terminating and bias-determining resistor 102. Between the cathode of tube 103 and ground are in parallel a cathode bias resistor 103a and by-pass condenser 103b.

Between the positive terminal of battery 118 and plate of the tube 103 are connected in series a feed resistor 121 and a coupling resistor 104. Between the junction of the resistors 121 and 104 and ground is connected a by-pass condenser 106. Between the plate of tube 103 and ground is connected an output circuit comprising blocking condenser 106a and potentiometer 105 in series, the variable contact of potentiometer 105 being connected to the grid of the triode amplifier tube 107. Between the cathode of the tube 107 and ground are connected in parallel a bias resistor 107a and by-pass condenser 107b. Between the positive end of the battery 118 and the plate of tube 107 are connected in series a feed resistor 122 and a coupling resistor 108, the junction of which is connected to one terminal of by-pass condenser 112, the other terminal of which is grounded.

Between the ground and plate of tube 107 is connected an amplifier output circuit including a first plate-cathode branch of a double unidirectionally conductive tube 113, in parallel with a rectifier circuit resistor 109. A blocking condenser 111 is connected from the junction of resistor 109 and the first cathode of tube 113. From this junction to the second plate of tube 113 is a smoothing and limiting resistor 115, and from the second plate of tube 113 to the grids of tubes 95 and 98 is a smoothing and limiting resistor 116. The cathode of the second plate-cathode branch of tube 113 is connected to the tap on resistor 117.

It will be understood that while condensers 106, 112, 103b, 105 and 111 have been described as by-pass and blocking condensers, the values of capacitance may be chosen less than if the amplifier circuits of tubes 103 and 107 were desired to amplify uniformly at all frequencies. Lowering the capacitance of any of these condensers decreases the ability of the amplifier circuits to amplify low frequency tones. Accordingly the entire filtering action from plate of tube 82 to the first cathode-plate branch of tube 113 is not concentrated in filter 101, but involves further discriminatory action of the amplifier circuits in favor of the higher tones.

In the operation of the modified form of the invention shown in Fig. 3, the energy from the pick-up device passes through the transformer 21 to the push-pull amplifier 80, where it is amplified and then passes through the transformer 83 to the second push-pull amplifier 87. Here it is further amplified and passes through the transformer 39 to the power amplifier 40 shown in Fig. 1, 75

thence through the transformer 41 to the loud-speaker 42 where it is reproduced as speech or music in the usual manner. The transmission from tubes 81 and 82 to tubes 87a and 87b is dependent upon the internal impedances of the tone control tubes 95 and 98, which in turn are dependent upon the potential of the grids of these tubes with respect to cathodes. In general lowered impedances of tubes 98 decrease the choking action of the primary winding of transformer 83 in a manner similar to that of similar elements of Fig. 1. This results in increased transmission of higher frequencies. On the other hand, the circuit 88 shunted from plate of tube 81 to plate of tube 82 is designed so that chokes 90 prevent the absorption of higher frequency energy, and this circuit modifies the transmission chiefly for low frequencies. The lowering of the internal impedances of tubes 95 results in a lowered primary impedance of transformer 92, and more loss of transmission for the low frequencies.

For producing control voltage, some of the energy from the output of tube 82 is fed through filter 101 to the grid of amplifier tube 103. The filter elements of 101 are of high impedance and the amount of energy diverted to amplifier 103 is relatively small. The filtered energy is selectively amplified by tube 103 and associated circuits, and impressed upon the grid of tube 107. It is again selectively amplified and impressed upon the first plate-cathode branch of the tube 113. This tube rectifies due to its unidirectional characteristics, since it passes current only when the cathode is negative with respect to the grounded plate. The rectifier resistor 109 carries A. C. tonal current and also rectified D. C. current, the direction of which is indicated by the arrow. As a result the D. C. potential of the first cathode becomes positive with respect to ground although the potential goes negative instantaneously when the rectifier is operating. The pulsations of potential of this cathode are smoothed out by resistors 115 and 116 in series, and condensers 95a, 95b, 98a, and 98b, so that a potential between grids and cathodes of the tubes 95 and 98 exists substantially devoid of the high tonal frequencies present in resistor 109. This potential changes with change of the amount of energy impressed upon the rectifier circuit. The second plate-cathode branch serves as a spillway for rectified energy whenever the potential of the plate exceeds the potential of the cathode which is the same as that of the tap on resistor 117. This makes the potential of the grids of tubes 95 and 98 change more on a proportionate basis when the tonal signal energy is low than when it is high. It is understood, however, that even if the limiting action of the second plate-cathode branch is not used, limiting actions will occur when the grids of tubes 95 and 98 become positive with respect to the cathodes, due to the resultant voltage drop through resistors 115 and 116.

As a result, increased energy impressed through amplifier tubes 103 and 107 upon the rectifier increases the potential of grids of tubes 95 and 98, decreases the ability of the coupling network from tubes 81 and 82 to tubes 87a and 87b to transmit low frequency tones and increases the ability of this coupling network to transmit higher frequency tones. This emphasizes the tonal contrast by providing a circuit which emphasizes low tones when high tones are absent, and emphasizes high tones and discriminates

against low tones when high tones are especially present.

The transmission characteristics may be better understood with reference to Fig. 4, in which transmission of various parts of the system is shown as dependent upon the frequency of the energy being transmitted. Curve 120 illustrates the transmission of energy through the control channel, showing the relative ability of energies of different frequencies at the secondary of transformer 21 to produce control potential on the grids of tubes 95 and 98. Curve 121 shows the relative transmission of energies of different frequencies from the transformer 21 to transformer 39 under the condition of the control circuit passing negligible energy, and curve 122 shows the same under the condition of passage of maximum potential change due to transmission of a sufficiently large amount of energy through the control circuit.

It will be understood that musical selections utilize volume contrasts and tonal contrasts. In addition to the use of the circuits of Fig. 1 and Fig. 3 to minimize surface noise effects, they may be used to emphasize the tonal contrasts. Thus at a given acoustical volume level, when the emphasis is intended to be upon the low tones, the circuits automatically increase the emphasis on the low tone, and when the emphasis is intended to be upon the high tones, the circuits automatically increase the emphasis on the high tones.

It will be understood, however, that the use of a transformer with an automatically variable loading is not limited to the arrangements specifically shown. For example, in Fig. 5 to Fig. 8 are shown typical insertion loss effects which can be achieved by use of certain transformer arrangements in combination with condensers and resistors. The curves of Fig. 6 show the insertion loss produced by the circuit of Fig. 5, when transformer 130 and primary condenser 131, with different secondary loadings due to resistor 137 and thermionic impedance in parallel, are cut in between resistors 132 and 133. The insertion loss is measured by the decibel decrease of energy to resistor 133 when switch 135 is transferred from the up position to the down position. Similarly the curves of Fig. 8 show the insertion loss producible by the arrangement of Fig. 7, for which the network consists of a transformer 142 with variable secondary loading, and with a condenser 140 and resistor 141 shunting the primary, the transfer switch connecting the transformer primary in parallel with the receiving resistor.

While in the circuit of Fig. 5 the variable impedance element especially controls the passage of high frequency tones, in the circuit of Fig. 6 it especially controls in an inverse sense the passage of low frequency tones.

This control may be in accordance with any desired tonal stimulus, with increased signal causing either increased or decreased loading. It will be understood that the invention is not limited to the arrangement of Fig. 1 or Fig. 3. For example it is within the scope of the invention to use the control arrangements of Fig. 7 and Fig. 8, in an automatic tonal compression device, for use in producing records. For this purpose the low secondary impedance $R_s = 10,000$ ohms would correspond to strong signals, and the amount of volume compression would be especially great for the lowest tones. Increased effects may be produced by using a plurality of tone control elements preferably in different stages of the

phonograph or talking picture recorder or reproducing amplifier.

While certain specific embodiments of the invention have been set forth for purposes of illustration, it is to be understood that various changes and modifications may be made therein as will appear to a person skilled in the art. The scope of the invention is only to be limited in accordance with the following claims when interpreted in view of the prior art.

What is claimed is:

1. In a system for recording or reproducing sound, a transmission channel having a filter network therein including a choke coil, said choke coil constituting a primary of a transformer, means applying a balanced load to the secondary of said transformer whereby variations in said load are prevented from reacting on the flux in the core of said transformer and means responsive to the signal energy for automatically varying said load so as to change the characteristics of said filter in accordance with the characteristics of said signal energy.
2. In a system for recording or reproducing sound, a transmission channel having a filter network therein including a choke coil, said choke coil constituting a primary of a transformer, a pair of variable impedance devices connected across the secondary of said transformer so as to provide a balanced load thereon, whereby the variations in load are prevented from reacting on the flux in the transformer core and means responsive to the signal energy for automatically varying the impedance of said devices so as to change the load on said transformer in accordance with the characteristics of the signal energy.
3. In a system for recording or reproducing sound, a transmission channel having a filter network therein, a transformer having a primary and a balanced secondary, said primary being disposed in said filter network, means applying a variable load to said secondary, said load being adapted to vary the effective primary impedance without substantially changing the flux density of the core, the primary impedance when the secondary is unloaded serving to prevent passage of the high frequency components of the signal and, when the secondary is loaded, serving to progressively pass more of said high frequency components, and means responsive to the certain frequency components of the signal for controlling said load.
4. In a system for recording or reproducing sound, a transmission channel having a filter network therein, a transformer having a primary and a balanced secondary, said primary being connected in said filter network so as to control the transmission characteristics thereof in accordance with the primary impedance, a pair of space discharge devices connected to the balanced secondary and adapted to variably load the same for altering the effective primary impedance of said transformer, a control channel responsive to certain components of the signal, means in said control channel to produce a control voltage proportional to the strength of said components and means applying said control voltage to said space discharge device so as to vary the impedance thereof in accordance with the strength of said components.
5. In a system for recording or reproducing sound, a transmission channel having a filter network therein, a choke coil in said network, means to vary the impedance of said choke coil without

changing the flux density thereof and means responsive to the signal energy for controlling said last means so as to vary the transmission characteristics of the filter in accordance with applied signal.

6. In a system for recording or reproducing sound, a transmission channel having a filter network therein, an inductive impedance in said network, means varying the value of said impedance in accordance with the applied signal and means to prevent such changes in impedance from causing a change in the direct current flux of said impedance whereby the timing is not influenced by the reluctance of the flux path.

7. In a system for recording or reproducing sound from a sound record, a transmission channel having a filter network therein including an inductive impedance device, and means applying a variable balanced load to said device which varies according to the signal energy, said load changing the effective impedance thereof and thereby altering the transmission characteristics of said filter.

8. In a system for recording or reproducing sound, a transmission channel having a filter network therein, a transformer having a primary and a balanced secondary, means applying a variable load to said secondary, means responsive to the signal energy for automatically varying said load in proportion to the change in signal energy, said primary being so disposed in said filter network that the impedance thereof, when the secondary is unloaded, prevents passage of high frequency components and an increase in the secondary load serves to lower the primary impedance so as to permit passage of the high frequency components.

9. In a system for recording or reproducing sound, a transmission channel having a filter network therein, a transformer having a primary and a balanced secondary, said primary being disposed in said filter network, means applying a variable load to said secondary, said load being adapted to vary the effective primary impedance without substantially changing the flux density of the core, the primary impedance, when the secondary is unloaded, serving to prevent passage of the high frequency components of the signal and, when the secondary is loaded, serving to progressively pass more of said high frequency components, and means responsive to the high frequency components of said signal for varying said load in proportion to the strength and frequency distribution of said components, whereby said components are passed by said filter network only when they are of a predetermined minimum strength.

10. In a system for recording or reproducing sound, a transmission channel having a filter network therein, a transformer having a primary and a balanced secondary, said primary being connected in said filter network so as to control the transmission characteristics thereof in accordance with the primary impedance, a pair of space discharge devices connected to the balanced secondary and adapted to variably load the same for altering the effective primary impedance of said transformer, a control channel responsive to the high frequency components of the signal, means in said control channel to produce a control voltage proportional to the strength of said space discharge devices so as to vary the impedance thereof in accordance with the strength of said components.

11. In a system for recording or reproducing

- sound, a transmission channel having a filter network therein, a transformer having a primary and a balanced secondary, said primary being connected in said filter network so as to control 5 the transmission characteristics thereof in accordance with the primary impedance, a pair of space discharge devices connected to the balanced secondary and adapted to variably load the same for altering the effective primary impedance of said transformer, a control channel responsive to the high frequency components of the signal, means in said control channel to produce a control voltage proportional to the strength of said components and means applying 10 said control voltage to said space discharge devices so as to change the impedance thereof inversely as the strength of said components whereby a balanced load is applied to said secondary which varies directly as the strength of 15 said components.
12. In a system for recording or reproducing sound, a transmission channel having a filter network therein, a transformer having a primary connected in said filter network and having a balanced secondary, means variably loading said secondary in accordance with the characteristics of the impressed signal for altering the effective primary impedance, the primary impedance, when the secondary is unloaded, being such as 20 to discriminate against the higher frequency components of the signal, the discrimination being progressively reduced as the secondary is loaded and, under conditions of maximum load, discriminating somewhat in favor of the lower 25 frequencies so as to compensate for the undercutting of the lower frequencies on the sound record.
13. In a system for recording or reproducing sound, a transmission channel having a filter network therein, a variable impedance in said network comprising the primary of a transformer, means to variably load the secondary of said transformer without changing the flux density and means responsive to the signal energy for 30 controlling said load so that signals in the background noise frequency range are only transmitted through said filter network when they are of such strength that the background noises will be masked thereby.
14. In a system for recording or reproducing sound, a transmission channel having a filter network therein, a transformer having a primary connected in said filter network to control, by its impedance, the transmission characteristics 35 thereof, a pair of variable impedance devices connected in balanced relation to said secondary for applying a balanced load thereto dependent upon their impedance, and means varying the impedance of said devices in accordance with the components of the signal which are normally suppressed by said filter.
15. In a system for recording or reproducing sound, a transmission channel having a filter network therein including a shunt choke coil, said choke coil constituting a primary of a transformer, means applying a load to the secondary of said transformer and means responsive to the signal energy for automatically varying said load so as to change the characteristics of said filter 40 in accordance with the characteristics of said signal energy.
16. In a system for recording or reproducing sound, a transmission channel having a filter network therein including a shunt choke coil, said choke coil constituting a primary of a trans- 45 former, a variable impedance device connected to variably load the secondary of said transformer and means responsive to the signal energy for automatically varying the impedance of said device so as to change the load on said transformer in accordance with the characteristics of the signal energy.
17. In a system for recording or reproducing sound, a transmission channel having a filter network therein, a pair of transformers having primary windings connected respectively in shunt and in series in said filter network, means applying a variable load to the secondary windings for varying the effective primary impedances, and means responsive to the strength and frequency 50 characteristics of the signal for varying said load so as to alter the transmission characteristics of the filter network.
18. In a system for recording or reproducing sound, a transmission channel having a filter network therein, a pair of transformers each having a primary and a balanced secondary, said primaries being connected respectively in shunt and in series in said filter network so as to control the transmission characteristics thereof in accordance with the primary impedances, a pair of space discharge devices connected to each balanced secondary and adapted to variably load the same for altering the effective primary impedance of the transformers, a control channel 55 responsive to certain components of the signal, means in said control channel to produce a control voltage proportional to the strength of said components and means applying said control voltage to said space discharge devices so as to change the impedance thereof inversely as the strength of said components whereby a balanced load is applied to the secondaries which varies directly as the strength of said components.
19. In a system for recording or reproducing sound having a transmission channel including a variable impedance device constituting the secondary of a transformer, the method of varying the impedance of said device which comprises applying a variable balanced load to the secondary which varies in proportion to the characteristics of the signal, and causing the changes in the secondary load to alter the effective primary impedance of the transformer in such manner that certain frequencies are suppressed by 60 the filter except when they are of a predetermined minimum strength.
20. In a system for recording or reproducing sound having a transmission channel including a filter network and a variable impedance device in said filter network comprising the primary of the transformer, the method of varying the transmission characteristics of said network which comprises variably loading the secondary of said transformer in accordance with the signal while 65 maintaining the flux density of said transformer substantially independent of said load.
21. In a system of the class described having an audio frequency transmission channel including a variable filter, the method of producing tonal contrast which comprises utilizing the average volume of the high frequency tones applied to said channel for varying the frequency transmission characteristics of said filter in such manner that the filter discriminates in favor of low 70 frequency tones when the high frequency tones are weak and discriminates in favor of the high frequency tones when the high frequency tones are strong.
